UNITED STATES PATENT OFFICE.

SAMUEL L. JOHNSTON, OF WALPOLE, MASSACHUSETTS.

MACHINE FOR WASHING WASTE, CLOTHS, &c.

SPECIFICATION forming part of Letters Patent No. 239,963, dated April 12, 1881.

Application filed October 15, 1880. (No model.)

To all whom it may concern:

Be it known that I, SAMUEL L. JOHNSTON, of Walpole, in the county of Norfolk and State of Massachusetts, have invented a new and useful Improvement in Machines for Washing Waste, Cloths, &c., of which the following is a specification.

The object of my invention is to produce a machine for washing cotton-waste, by means of which a great saving of time is effected in comparison with the ordinary process, and the waste is left in an open loose condition, without any loss of material, together with other advantages hereinafter set forth.

15 The invention consists of an elongated box or receptacle, suspended by cords near each end from the upper part of a frame or from the ceiling of a room, to which a longitudinal shaking or oscillating motion is imparted 20 through a pitman suitably attached and connecting with a crank operated by any suitable power.

25 The receptacle may be divided to form two or more compartments, each compartment having a wire netting or screen at each end communicating with a narrow passage through which the water, after being used, passes into an open receptacle below.

30 The invention further consists in a means of supplying water to the machine, while it is in operation, through a flexible tube to a series of branch pipes connected to the top of the machine. Underneath the openings of these branch pipes are screens, through which the 35 water passes in the form of spray or shower upon the waste as the machine is oscillated, thus providing a constant supply of clean water, while the dirty water is at the same time discharged at the bottom of the machine.

40 My invention is illustrated in the accompanying drawings, in which Figure 1 is a side elevation. Fig. 2 is a transverse vertical section on the line $x-x$ of Fig. 1. Fig. 3 is a plan or top view. Fig. 4 is a longitudinal vertical section on the line $x'-x'$ of Fig. 3. Fig. 5 is 45 an enlarged view, in detail, on the line $y-y$ of Fig. 3, showing the connection of a branch pipe with a recess and screen. Fig. 6 is also an enlarged view on line $z-z$ in Fig. 3.

50 Similar letters indicate like parts in the several figures.

A represents the main box or receptacle for

the waste, and may be divided into two or four compartments, each compartment extending from the ends to the center, or nearly so, of the 55 box A. The said box is suspended at $b'-b'$, by means of cords or wires $b-b$, from the upper part of a frame, B c c, or the said cords may be attached to a beam at the top of a room.

C is a pitman, shown as connected to a shaft 60 or rod, d, arranged on the top of the machine, and to a crank, e, on the shaft of a wheel, to which motion is imparted by any suitable power, by means of which a longitudinal reciprocal motion is imparted to the box A. Near the end 65 of each compartment A' is a wire screen or netting, s, extending across the compartment from top to bottom, and between the screens and the ends of the compartments are passages $p-p$, for the exit of the dirty water out of 70 the same, which is discharged into a receptacle, D, below the box A.

Extending lengthwise of the box A, on the top of the same, is a pipe, E, from each side of which extend branch pipes $f-f$. The ends 75 of these branch pipes open into recesses $g-g$, formed on the under side of the top of the box A and extending transversely nearly across the same. At the bottom of the recess g is a wire screen or netting, S, through which the 80 water falls upon the waste in the form of spray or shower, thus furnishing a constant supply of clean fresh water during the process of cleansing the contents of the box. Water is supplied to the main pipe E by means of a 85 flexible pipe, P, connecting with any suitable source of supply, so as to admit of a steady flow of water while the machine is in operation.

h h represent small covers, provided with 90 handles $h'-h'$ and fitted to holes in the upper part or covering of the machine, for feeding the waste to the box A.

Although my machine is described as especially adapted for cleaning cotton-waste, it is 95 equally efficient for washing clothes or cloths of any description.

In the ordinary machines for cleaning waste, where dash-wheels are used, the waste becomes 100 rolled and tangled up, while my process leaves it in an open, loose condition, and takes much less time in the operation, and the material suffers no loss.

The waste in my process gets the full bene-

fit of all the water, and none is wasted as in other processes. The machine makes no dirt, and is almost noiseless in operation. It takes less power to operate than a dash-wheel, while 5 doing double the amount of work.

It will be perceived that at the end of each throw of the machine it is slightly elevated from its level at its central position, which motion tends to shake up the waste as it is 10 pounded against the screens and more effectually drive out the dirt, which is carried off through the screens and discharged through the passages *p p*, as before explained.

A single compartment, *A'*, may be used, if 15 found desirable.

What I claim as my invention is—

1. A machine for washing cotton-waste or other material, consisting of a rectangular reciprocating box, *A*, having two or more compartments, *A'*, each compartment being pro- 20

vided with screens *s* and passages *p*, substantially as and for the purpose set forth.

2. The combination, with the reciprocating box *A*, of the cover provided with the recesses *g g*, the screen *S*, the main pipe *E*, and the 25 pipes *f f*, as and for the purpose specified.

3. The combination of the reciprocating box *A*, the cover provided with the recesses *g g*, the screens *S*, the supply-pipe *E*, branch pipes *f*, and flexible pipe *P*, all arranged and operating substantially as and for the purpose described. 30

In testimony whereof I have signed my name to this specification in the presence of two subscribing witnesses.

SAMUEL L. JOHNSTON.
